[57] CLAIM

The ornamental design for a combined spoon and
scoop, substantially as shown and described.

DESCRIPTION

FIG. 1 is a front elevational view of a combined spoon
and scoop showing my new design;

FIG. 2 is a rear elevational view thereof;

FIG. 3 is a top plan view thereof;

FIG. 4 is a bottom plan view thereof;

FIG. 5 is a left end elevational view thereof;

FIG. 6 is a right end elevational view thereof; and

FIG. 7 is a top and front perspective view thereof on an
enlarged scale.
